(57) **CLAIM**

The ornamental design for a bicycle fork crown, as shown and described.

DESCRIPTION

FIG. 1 is a perspective view of the bicycle fork crown showing my new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof;
FIG. 7 is a bottom plan view thereof;
FIG. 8 is a perspective view from another angle of view thereof;
FIG. 9 is a perspective view from another angle of view thereof;
FIG. 10 is a perspective view from another angle of view thereof;
FIG. 11 is a view showing the application thereof; but show installed on the bicycle forks in a configuration of use for clarity of illustration; and,
FIG. 12 is a view showing the application thereof, but show installed with the extension part in a configuration of use for clarity of illustration.
The dashed broken lines in the FIGS. 11-12 are included for the purpose of illustrating portions of the bicycle fork crown and form no part of the claimed design.

1 Claim, 12 Drawing Sheets
